UNITED STATES PATENT OFFICE.

ERNST MENNEL, OF DARMSTADT, GERMANY, ASSIGNOR TO LOUIS MERCK,
E. A. MERCK, WILLY MERCK, AND C. E. MERCK, OF SAME PLACE.

PROCESS OF MAKING ACIDYL MORPHIN ESTERS.

SPECIFICATION forming part of Letters Patent No. 650,408, dated May 29, 1900.

Application filed August 9, 1899. Serial No. 726,698. (No specimens.)

To all whom it may concern:

Be it known that I, ERNST MENNEL, a subject of the Emperor of Germany, residing at Darmstadt, Germany, have invented a certain new and useful Chemical Process, of which the following is a full, clear, and exact description.

Carboxy-alkylic esters of morphin prepared according to Otto's process possess but little stability and little tendency to crystallize. Their acidyl compounds, on the other hand, exhibit decided crystallizability and comparative stability. I have found that such compounds can be obtained from the simple aliphatic-acidyl-morphins of the fatty-acid series—as, for instance, acetyl-morphin, propionyl-morphin, &c.—by treating the same with chlorocarboxylic esters and alkali, preferably in molecular proportions.

Carboxy-alkylic esters of morphin, as mentioned by Otto, are represented by this general typical formula:

in which R' signifies any univalent alcohol radical, (or alkyl.)

The carboxy-alkylic esters of acidyl-morphins, which form the subject of my invention, are represented by this general typical formula:

in which R' signifies as before, and A' signifies any acid radical (or acidyl) of the fatty series.

The reaction by which the carboxy-alkylic esters of acidyl-morphins are formed in my process is represented by the following equation:

in which R' and A' signify as before, and M'

signifies an alkali metal, (univalent in the instance here shown;) or (the above equation being translated into common language)

Taking an actual specific example, in which A' shall signify acetyl and R' shall signify ethyl and M' shall signify potassium, the above equation takes the following form:

In a similar double decomposition, only using other chlorocarboxylic esters instead of the ethyl ester, as above, we obtain, for instance, carboxy-methylic ester of acetyl-morphin:

or carboxy-propylic ester of acetyl-morphin:

&c. Also by using other acidyl-morphins—as, for instance, propionyl-morphin or butyryl-morphin—instead of the acetyl-morphin we can vary the composition of the product in its other side chain. Other alkalies—as, for instance, sodium hydroxid—can also be substituted for the potassium hydroxid as the agent for inducing the above-recited reaction; but this will not yield a different product, but is merely a variation possibly bearing on the convenience of manipulation or the economy of the process.

As an example of my process, a suitable acidyl-morphin, being suspended in benzene, is shaken at ordinary temperatures with the

two reagents, the ester having been added in bulk, whereas the alkali in aqueous solution is only allowed to flow into the mixture in successive small portions, so as to avoid any splitting of the acidyl-morphin by free alkali. The reaction takes place immediately during the shaking, the newly-formed compound going into solution with the benzene, while the alkali chlorid formed as a by-product is found dissolved in the aqueous liquor. The reaction being completed, the benzene solution is siphoned off, washed, and dried. On evaporating the solvent herefrom the acidyl-morphin carboxy-alkylic ester in a nearly-pure state is found as the residue.

Example of manufacture.—*Acetyl-morphin carboxy-ethylic ester.*—One thousand grams of alpha-acetyl-morphin, finely powdered, is suspended in twelve kilograms of benzene and three hundred and thirty grams of chlorocarboxylic ethylester is added. Into this mixture one hundred and sixty-one grams of potassa in about ten-per-cent. solution is allowed to flow in small portions, while the mixture is vigorously shaken. When the alkaline solution has all been added, the previously-prevailing odor of the chlorocarboxylic ethyl ester disappears. After the settling of the liquids the benzenic stratum is siphoned off. This part having been washed with water and then dried, the benzene is distilled off. The desired ester in nearly a pure state remains as a solid crystalline mass. By recrystallizing it from three to four times its bulk of absolute alcohol it is obtained in beautiful glass-like needles or prisms, which melt at 150° centigrade. By treating the product, finely powdered, with its exact molecular equivalent of titrated hydrochloric acid the hydrochlorate of the product is obtained in small colorless needles, which melt at 185° centigrade under evolution of gas. These needles, in combination with platinic chlorid, yield a platinum double salt, which crystallizes in

orange-colored little needles and whose melting-point is about 210° centigrade.

Acetyl-morphin carboxy-methylic ester is made by the same procedure as above described, the chlorocarboxylic ethyl ester being replaced by an equivalent of chlorocarboxylic methyl ester. The product appears in coarse prismatic crystals, which melt at 168° centigrade. Acetyl-morphin carboxy-propylic ester is also made in the same way, using chlorocarboxylic propyl ester. The product crystallizes in colorless needles, melting at 120° centigrade. These and other similar forms of product obtainable by my above-described process may be usefully employed as medicinal agents.

It will be obvious that many changes may be made in the disclosure herein without departing from the spirit of my invention.

What I claim is—

1. The process of preparing a carboxy-alkylic ester of an acidyl-morphin, which consists in treating an alpha-mono-acidyl compound of morphin, whose acidyl constituent is of the fatty-acid series, with a chlorocarboxylic ester and an alkali.

2. The process of preparing a carboxy-alkylic ester of an acidyl-morphin, which consists in treating an alpha-mono-acidyl compound of morphin, whose acidyl constituent is of the fatty-acid series, with a chlorocarboxylic ester and an alkali, the same being used in molecular proportions.

3. The process of treating alpha-mono-acetyl-morphin with chlorocarboxylic ethyl ester and an alkali, thereby producing the carboxy-ethylic ester of acetyl-morphin.

Signed at Darmstadt, Germany, this 20th day of July, 1899.

ERNST MENNEL.
